UNITED STATES PATENT OFFICE.

HANS STÖCKER, OF NUEREMBERG, GERMANY, ASSIGNOR TO THE FIRM OF WECKER-LEIN & STÖCKER, OF NUEREMBERG, GERMANY.

APPARATUS FOR STARTING MULTIPLE-CYLINDER INTERNAL-COMBUSTION MOTORS.

1,090,580.

Specification of Letters Patent. Patented Mar. 17, 1914.

Application filed June 19, 1912. Serial No. 704,590.

To all whom it may concern:

Be it known that I, HANS STÖCKER, a citizen of the Empire of Germany, residing in Nuremberg, Bavaria, Germany, have invented certain new and useful Improvements in Apparatus for Starting Multiple-Cylinder Internal-Combustion Motors, of which the following is a specification.

It was hitherto proposed to start multiple-cylinder internal combustion motors by means of automatic ignition devices, which however had the drawback that only a single spark was produced by operation of the magneto, and the spark was generally not sufficiently powerful to ignite the gaseous mixture for starting the motor. It was also proposed to employ an auxiliary magneto for starting, but the use of such a magneto had the great disadvantage of requiring the manual operation of special switches.

The present invention has for its object to provide a starting apparatus comprising an auxiliary magneto, in which the above-stated drawbacks are remedied. In the improved apparatus, on turning the starting handle of the auxiliary magneto a series of sparks is produced in the respective cylinder, which heats up the gaseous mixture surrounding the spark to such a high degree as to insure ignition. By means of a special device the switching on and off is effected entirely in an automatic manner on turning the handle of the auxiliary magneto, no other manipulation being necessary. Further, by using a special circuit-making device the switching-in is arranged to take place in such manner that it is impossible for the gaseous mixture to become ignited before the motor piston has reached its highest dead center. Hence no backfiring can take place, and the motor is always obliged to start in normal direction.

One form of the improved apparatus is illustrated in the accompanying drawing, in which—

Figure 1 is a side elevation, with parts in section, of the auxiliary magneto and its connections, and Fig. 2 is a diagram showing the connections.

Similar letters of reference indicate like parts in the views.

The armature a^1 of the auxiliary magneto is driven by means of a gear a , and pinion b . The gear-wheel a is loosely mounted on a suitable longitudinally-mov-

able axle c , and is provided at its hub b^1 with a shoulder a^2 from which an inclined surface a^3 leads to a second shoulder, a^4 , removed 90 degrees from the first shoulder. The axle c is rotatable by means of a crank-handle d , and carries a radial pin e which is adapted to move over the inclined face a^3 and thus cause the axle c to shift endwise. The wheel a is prevented from axial movement endwise of the shaft c by engagement of its hub b^1 with a bracket b^2 of the magneto frame. Rotation of the shaft by its handle thus first causes the shaft to be shifted longitudinally against the tension of its helical compression spring n , until the pin e arrives at the shoulder a^4 , namely, for a quarter of a rotation of the handle no movement of the gear-wheel a occurs. The pin e having arrived at the shoulder a^4 , on continued movement of the handle the gear-wheel is carried along and continuously rotated so long as the handle is turned.

The endwise movement of the axle c causes it to engage and move outwardly a switch-lever f mounted at the rear of the auxiliary magneto. A block of insulating material f^1 is mounted at the rear of the magneto, and in said block are three terminals, g , h and k respectively. The switch-lever f is normally retained by its actuating spring f^2 against contact g . Said spring actuates a sliding button f^3 which is in constant engagement with terminal k . Hence when the axle c shifts the switch f , the switch breaks circuit between k and g , and establishes circuit between k and h . The high tension current now generated by the operation of the auxiliary magneto passes from brush-holder i of said magneto to terminal h , through lever f , contact k and lead l , to the distributor m of the main magneto. Here the high tension current passes through the distributing arm m^1 to that particular contact with which the arm is in engagement and which is not shown in Figs. 1 and 2 as the same is covered by the arm m^1 , and from said contact to the spark-plug of the cylinder with which the contact is electrically connected. The charge being thus exploded in the cylinder, the motor starts, and rotates the armature o of the main magneto. The auxiliary magneto may continue to be rotated by hand, and will continue to produce high tension current and deliver the same to the distributor of the

main magneto, whence it is distributed in the usual manner successively to the cylinders. So long as the auxiliary magneto is kept in operation, no current from the main magneto reaches the distributor m . When rotation of the auxiliary magneto is discontinued, spring n moves the axle c longitudinally forward into its position of rest. Thereby switch-lever f is permitted to 5
10 treat from terminal h , and to close connection between terminals g and k . Thus the high-tension current from main magneto armature o , arriving at g , now passes through switch f and terminal k , to the distributor m , and no current is supplied from 15
15 the auxiliary magneto because the connection between the terminal h of said magneto and the terminal k of the distributor m is interrupted. The motor continues in normal 20
20 operation ignited only by the high tension current from the main magneto o .

The adjustment of the segments m^2 of the distributor plate is such as is adapted for rapid rotation of the motor, but the 25
25 sparks produced thereby are so far advanced that for the slow rotation of starting there is danger of backfiring. To avoid the difficulties of starting, due to this arrangement of the segments, a separate 30
30 auxiliary circuit-breaker is placed in the primary of the auxiliary magneto, so that said magneto supplies current not continuously, but only during a portion of the time 35
35 the distributing arm m^1 is in contact with the respective segment. Such device is shown diagrammatically in Fig. 2, and comprises a rotating arm s suitably connected to the main magneto armature-shaft and movable over two contact-plates s^1 s^2 . The 40
40 arm is grounded, and the contact-plates are both connected to the primary lead p of the auxiliary magneto. The mechanical adjustment is such that the rotating arm s passes upon the segments s^1 s^2 and thereby short-circuits the primary winding of the auxiliary magneto at those times during the contact 45
45 between the distributor arm m^1 and segments m^2 when the piston of the cylinder controlled by the respective segment m^2 has 50
50 not reached its highest dead center. For example, in a four-cylinder motor, it is customary to adjust the segments m^2 so that each of the same is struck by the arm m^1 before the dead center of the piston is 55
55 reached, and the contact continues for approximately three-fourths of the piston stroke. But for starting, it is desirable not to fire the charge before the piston passes the dead center. Hence, the contact-plates 60
60 s^1 , s^2 , are so arranged as to short-circuit the primary of the auxiliary magneto and pre-

vent thereby said magneto from furnishing current during that portion of the rotation of arm m^1 when said arm is passing the first part of each segment m^2 , namely that portion representing the time when the respective piston is not yet arrived at dead center and is therefore not ready for the explosion. 65

When operation of the motor by means of the auxiliary magneto is discontinued, 70 normal operation of the distributor m is permitted, because the auxiliary magneto being cut out entirely, the circuit-breaker s , s^1 , s^2 is also out of the circuit, and the main magneto o furnishes current uncontrolled by 75 said circuit-breaker.

The motor may be operated at slow speed for any desired length of time by continued manual operation of the auxiliary magneto. This is of value in case of failure of the 80 main magneto. It is obvious that for starting, it is necessary to previously leave the motor with the throttle-valve turned open so that the cylinders are supplied with fuel for the starting explosions, and it is also 85 necessary to leave the apparatus in such position that the distributor arm m^1 is in contact with one of the segments m^2 . When these conditions are fulfilled, the motor may be started in the manner described by simply 90 rotating the auxiliary magneto, no rotation or cranking of the motor itself being required.

I claim:

An apparatus for starting internal combustion motors, comprising a main magneto having a distributor, a manually-operable auxiliary magneto, a switch adapted to break the high-tension circuit of the main magneto and place the auxiliary magneto in 100 connection with the main magneto distributor, manually-operable means for moving said switch prior to operation of the auxiliary magneto, automatically acting means for returning said switch to establish 105 the high tension circuit through the main magneto on discontinuance of manual operation of the auxiliary magneto, and a circuit-breaker connected with the primary of the auxiliary magneto, and operated by the main 110 magneto, for breaking the primary circuit during the initial portion of the ignition contact at the distributor for each cylinder respectively.

In testimony, that I claim the foregoing 115 as my invention, I have signed my name in presence of two subscribing witnesses.

HANS STÖCKER.
